UNITED STATES PATENT OFFICE.

WILLIAM E. COPENHAVER, OF SPRINGFIELD, OHIO, ASSIGNOR TO THE FOOS MANUFACTURING COMPANY, OF SAME PLACE.

DESIGN FOR A GRINDING-PLATE.

SPECIFICATION forming part of Design No. 34,544, dated May 21, 1901.

Application filed April 17, 1901. Serial No. 56,325. Term of patent 7 years.

To all whom it may concern:

Be it known that I, WILLIAM E. COPENHAVER, a citizen of the United States, residing at Springfield, in the county of Clark and State of Ohio, have invented and produced a new and original Design for Grinding-Plates, of which the following is a specification, reference being had to the accompanying drawings, forming a part thereof, wherein—

10 Figure 1 is a plan view of a grinding-plate embodying my design; and Fig. 2 is a sectional view of the same, taken on the line *xx* of Fig. 1.

As shown in the drawings, the leading or material feature of my design consists in a grinding-plate having a flat body 1, bounded on opposite sides by concentric circular margins 2 and 3 and straight lateral edges 4 and 5, drawn radially from the common center of 20 the other two edges. Upon the upper surface of this body are three concentric ribs 6, 7, and 8 of equal height, defining two annu-

lar spaces 9 and 10. In each of these spaces there are transversely-inclined ribs 11, joining each other in V shape, as shown, and having a height equal to the height of the annular ribs, between which they extend, and into each of the V-shaped spaces thus formed there extends from the adjacent annular rib a V-shaped projection 12, having its sides parallel with the ribs 11, these projections being the same height as the ribs.

Having thus fully described my invention, what I claim as new, and desire to secure by Letters Patent, is—

35 The design for a grinding-plate, substantially as herein shown and described.

In testimony whereof I have signed my name to this specification in the presence of two subscribing witnesses.

WILLIAM E. COPENHAVER.
